(57) **CLAIM**

The ornament design for a material for packaging, as shown and described.

DESCRIPTION

FIG. 1 is a front perspective view of the material for packaging;

FIG. 2 is a rear perspective view thereof;

FIG. 3 is a front elevational view thereof;

FIG. 4 is a right elevational view of the material for packaging shown in FIG. 1, the left side being a mirror image thereof;

FIG. 5 is a top plan view thereof;

FIG. 6 is a bottom plan view thereof; and,

FIG. 7 is a rear elevational view of the material for packaging shown in FIG. 1.

The color or surface finish of the material for packaging form no part of the claimed design.
